Primary Examiner — Richard E Chilcot(74) *Attorney, Agent, or Firm* — Margaret Polson; Polson Intellectual Property Law PC(57) **CLAIM**

The ornamental design for an intelligent carrying robot, as shown and described.

DESCRIPTION

1.1 is a front view of an intelligent carrying robot showing our new design;

1.2 is a back view thereof;

1.3 is a left side view thereof;

1.4 is a right side view thereof;

(Continued)

- 1.5** is a top view thereof;
1.6 is a bottom view thereof;
1.7 is a perspective view thereof;
1.8 is a perspective view of use state thereof.

1 Claim, 6 Drawing Sheets
